(57) **CLAIM**

The ornamental design for a oil filter removal tool, as shown and described.

DESCRIPTION

FIG. 1 is a front elevational view of an oil filter removal tool according to an embodiment of the design;

The rear, right and left elevational views of the oil filter removal tool are identical to the front elevational view;
FIG. 2 is a bottom plan view of the oil filter removal tool;
and,

FIG. 3 is a top plan view of the oil filter removal tool.
The broken lines depict portions of the oil filter removal tool that form no part of the claimed design.
